PUMP

Henry Crewdson, West Chester, Pa., assignor to
American Viscose Corporation, Marcus Hook,
Pa., a corporation of Delaware

Application April 8, 1938, Serial No. 200,995

6 Claims. (CL 103—218)

This invention relates to pumps and it is an object of this invention to provide an improved construction for pumps which will permit of pipe connections being made to the pump in such manner that the connection can be made or broken without the connecting or disconnecting of threaded joints and that the connections can be made secure against leaks when passing liquids without subjecting the pump casing of pressures tending to distort the casing and increase the operating friction of the pump.

In the drawings:

Figure 1 is a view partly in elevation and partly in vertical section of a pump in accordance with this invention;

Figure 2 is a view in longitudinal section of the pump shown in Figure 1 taken in the plane of the axis of the pump and its supporting trunnions; and

Figure 3 is a view in vertical section taken as on line 3—3 of Figure 1.

In the drawings the invention is shown in connection with a pump 1 of a type suitable for the pumping of viscose solutions to the spinning head used in the forming of rayon threads. The pump 1 is shown mounted in a support 2 having a base portion 4 and standards 5 and 6, the base portion 4 being shaped at its ends to fit about a supply pipe 8 to which it is secured by clamp members 10 and bolts 12. The standard 5 is drilled throughout its length providing a bore or passage 14 which is enlarged at both ends; at its lower end to receive a tubular bushing 15 which projects from the support 2 to fit into an opening in the supply pipe 8. The upper portion of the bore 14 is enlarged to form a valve chamber and threaded to receive a threaded needle valve 16 and the upper end of the valve chamber is enlarged to receive the packings 17 and the packing gland 18 which serves to compress the packings 17 to prevent leakage from the valve chamber.

Extending transversely of the standard 5 and intersecting the bore or passage 14 is a second bore or passage 20 which is closed at one end by a threaded plug 22 and is enlarged at its other end to receive a trunnion 24 which is threaded in an opening in the casing 26 of the pump 1. The bore 20 is enlarged beyond the size necessary to receive the trunnion 24 in order to receive a packing 28 and a packing gland 30 which serves to compress the packing 28 to prevent leakage from the bore 20. The trunnion 24 is provided with a bore aligned with the bore 20 and completes a

passage from the supply pipe 8 to the intake port of the pump 1.

The pump 1 is shown as comprising a substantially cylindrical casing 26 closed at its ends by the end or cap pieces 32 and 34, respectively, and having rotatably mounted therein a barrel 36 formed with a plurality of plunger bores 38 and a stem 36a. The stem 36a projects through the cap piece 32 and is of reduced diameter at its outer end portion to receive a gear 40 which is fixed on the stem 36a by a set screw 41. The bores 38 of the barrel 36 are connected in turn, as the barrel is rotated, with the intake port in the casing to receive liquid supplied through the bore in the trunnion 24 and with a discharge port in the casing which is connected with a bore or passage in a second trunnion 42. Plungers 44 slidably mounted in the bores 38 have substantially spherical heads 46 engaged between slippers 47 and 48 slidably engaging plates 50 and 49, respectively. Spacing rollers 52 mounted in the plates 49 and 50 aid in guiding the slippers 47 and 48. The plates 49 and 50 are held inclined to the axis of the plungers 44 by being mounted on an inclined pin 51 fixed in a support 54 which projects through a slot in the cap piece 34.

The support 54 is formed at its inner end with an enlarged portion 54a having a surface 54b formed as a portion of a sphere and which engages a correspondingly shaped surface forming part of the inner face of the cap piece 34. The support 54 is slotted to receive the spherical end of an adjusting screw 56 mounted in the cap piece 34 for adjusting the angular position of the support 54 and pin 51 and the outer end of the support 54 is threaded to receive a bolt 58 by which a washer 59 having a surface formed as part of a sphere is held in engagement with the correspondingly shaped outer face of the cap piece 34. A lock washer 60 between the washer 59 and the head of the bolt 58 prevents loosening of the bolt and a plate 62 mounted on the pin 51 and held against rotation thereon prevents wear of the end portion 54a of the support 54. Such wear as results from the operation of the pump is distributed on the plates 49 and 50 and the slippers 47 and 48 may be compensated for by adjustment of the pin 51 which is readily accessible through removal of the cap piece 34.

The trunnion 42 is threaded into the pump casing 26 directly opposite the trunnion 24 and is provided with spaced shoulders 42a and 42b positioned to receive between them a curved seat portion 64 formed in the upper end of the inner fork 6a of the standard 5. A cap piece 61 secured

to the standard by a bolt 63 secures the trunnion 42 in position. The outer end of the trunnion 42 is of spherical shape to fit an opening in a mounting lug 70 of a filter 72 to which the pipe (not shown) which leads to the spinning head is connected. A bore or passage 72a in the lug 70 serves to lead the liquid from the passage in the trunnion 42 to the filter and thence to the pipe leading to the spinning head. The mounting lug 70 is held in engagement with the trunnion 42 by a plug 64 slidably mounted in a recess in a plug 66 threaded in the outer fork 6b of the standard 6, a ball 68 being inserted between the plug 64 and the inner end of the recess. The plug 66 is provided with openings 69 to receive a tool for rotating the plug.

Mounting the pump on trunnions and connecting the filter thereto in the manner described permits of the filter being disconnected and the pump being removed from its support for inspection or repair without the necessity of breaking or disconnecting any threaded pipe joints. Adjustment of plug 66 insures the filter being held to the trunnion so as to prevent leakage at the joint and does not place additional pressure on the pump casing as the thrust of the plug 66 is resisted by the engagement of the collar 42a on the trunnion 42 against the fork 6a of the standard 6 and no pressure transmitted to the pump casing to increase the operating friction of the pump. Any slight movement of the trunnion 42 necessary for the collar 42a to engage the fork 6a is permitted by the slip joint mounting of the trunnion 24 in the standard 5 which allows the trunnion 24 to slide in the packing 28 and gland 30 to insure the pressure being resisted by the collar 42a and standard 6 and not by the trunnion 24 and pump casing while, at the same time, providing a leak-proof connection for the flow of liquids from the standard 5 to the pump.

What is claimed is:

1. The combination of a pump having a casing, trunnions fixed to said casing and having passages for fluid therein, a base having standards supporting said trunnions, means forming a continuation of the passage in one of said trunnions, means mounted on the standard supporting said one trunnion for forcibly holding said first mentioned means against the end of said trunnion to establish a passage from said one trunnion to said first mentioned means and means on said one trunnion engaging its supporting standard to prevent transmission of pressure through said trunnion to said pump.

2. The combination of a pump having a casing, trunnions fixed to said casing, a base having standards supporting said trunnions, one of said trunnions and its supporting standard being at

all times arranged for axial movement of said trunnion in either direction with respect to said standard to prevent compressive strains on said casing and the other trunnion and standard having cooperating means preventing all axial movement of said trunnion.

3. The combination of a pump having a casing, trunnions fixed to said casing and having passages for fluid therein, a base having standards supporting said trunnions, one of said standards having a passage for fluid therein and said standard and its cooperating trunnion having a slip-joint connection at all times permitting axial movement of said trunnion in either direction to prevent compressive strains on said casing and the other standard and its cooperating trunnion having cooperating means preventing axial movement of said trunnion.

4. The combination of a pump having a casing, trunnions fixed to said casing and having passages for fluid therein, a base having standards supporting said trunnions, one of said standards having a passage for fluid therein, said standard and its cooperating trunnion having a slip-joint connection permitting axial movement of said trunnion, means supported by the other of said standards for forcibly holding to the free end of the other of said trunnions a device forming an extension of the passage in said other trunnion and means on said other trunnion engaging its standard to prevent axial movement of said trunnion.

5. The combination of a pump having a casing, trunnions fixed to said casing and having passages for fluid therein, a base having standards supporting said trunnions, one of said standards being forked, and means in one fork of said divided standard for forcing against the end of the trunnion supported by said divided standard a device supported by said means and trunnion and forming a continuation of the fluid passage of said trunnion and means on said trunnion cooperating with said standard to prevent transmission to the pump casing of the force applied to said trunnion.

6. A mounting for a pump comprising trunnions fixed to the casing of the pump and having passages for fluid therein and a base having standards supporting said trunnions, one of the standards having a passage for fluid therein and one of said standards and its cooperating trunnion having a slip joint connection permitting axial movement of said trunnion in either direction at all times, and the other standard and its cooperating trunnion having cooperating means preventing axial movement of said trunnion.

HENRY CREWDSON.
